(57) **CLAIM**

The ornamental design for a cleaning sheet, as shown and described.

DESCRIPTION

FIG. 1 is a perspective view of a detail of the front and side surfaces of the cleaning sheet showing the new design and repeating pattern thereof;

FIG. 2 is a front plan view of the cleaning sheet;

FIG. 3 is a left side elevational view thereof;

FIG. 4 is a right side elevational view thereof;

FIG. 5 is a top view thereof;

FIG. 6 is a bottom view thereof; and,

FIG. 7 is a rear elevational thereof.
